A. N. OTIS

FURNACE

Filed July 16, 1925

Inventor:
Albert N. Otis,
His Attorney.

UNITED STATES PATENT OFFICE.

ALBERT N. OTIS, OF SCHENECTADY, NEW YORK, ASSIGNOR TO GENERAL ELECTRIC COMPANY, A CORPORATION OF NEW YORK.

FURNACE.

Application filed July 16, 1925. Serial No. 44,106.

My invention relates to furnaces and the like, and has for its object the provision of a simple, reliable and efficient means for applying and removing the cover.

5 My invention has particular application in the operation of the heavy heat insulated covers which are used on vertical electric furnaces, melting pots, etc. In carrying out 10 my invention I provide means whereby the cover is first lifted and then swung to one side.

15 For a more complete understanding of my invention reference should be had to the accompanying drawing in which Fig. 1 is a vertical section view of an electric furnace embodying my invention, the cover being shown in closed position; Fig. 2 is a fragmentary vertical section view showing the 20 cover in raised position, Fig. 3 is a plan view showing the cover partially swung to one side, while Fig. 4 is a fragmentary view showing a modified form of my invention.

25 Referring to the drawing, I have shown my invention in one form as applied to an electrically heated furnace 10 of the vertical type, i. e., the furnace opening is at the top. The heating chamber 11 is cylindrical in form, the central axis of the cylinder being substantially vertical. This chamber is defined at the sides by an inner layer 30 of heat refractory bricks 12 which are surrounded by suitable powdered heat insulating material 13, similar bricks being provided at the bottom, and the whole being enclosed in a metallic casing or jacket 14. Resting on the bricks 12 is a heavy heat 35 refractory member 15 provided with a central opening 16 through which access is had to the furnace chamber. A suitable insulating packing material 17 is provided around the member 15, an annular space of trough being left above the packing 17 which is filled with loose sand 18.

40 A circular flat cover 19, suitably heat insulated, rests on the member 15. This cover consists of an outer ring shaped metallic member 20 having an internal flange 21 near its lower edge which rests on the outer edge of the member 15. The ring member 20 extends 45 downward beyond the flange 21 for a short distance, and is beveled from the inside out to form an annular sealing lip or ring 22 which is forced downward into the sand 18 when the cover is put in place, as

55 indicated in Fig. 1. Preferably the upper end of the member 15 is beveled, as indicated by the reference numeral 23, so as to have substantially the same incline as the inner wall of the sealing ring 22. The sealing ring 22 is somewhat larger than the upper beveled 60 end of the member 15, the space between them being filled with the loose sand. A circular slab 24 of suitable heat insulating material is supported on the flange 21. This slab extends over the mouth 16 of the furnace and rests on the member 15, its lower face being flush with the lower side of the flange 21. Above the slab 24 the ring 20 is 65 filled with powdered heat insulating material 25, and the ring is closed at the top by 70 means of a circular metallic plate 26.

Any suitable heating means may be provided for the furnace. As shown, the furnace is heated by means of two electric resistors 27 and 28 which are bent in zigzag 75 form into a series of loops and hung on pins 27^a secured to the bricks 12. These resistors are placed one above the other in the interior of the furnace chamber, and each extends circumferentially around the chamber. The 80 depending loops 28 of the resistors are spaced by means of insulators 29 carried by suitable pins which are secured to the bricks 12.

For the purpose of facilitating the removing and replacing of the cover 19, I have provided a substantially horizontal arm 29 which is pivotally mounted at one end on a bracket 30 secured to the side of the furnace. As shown, the bracket 30 is provided with a substantially vertical pivot post 31 on which the arm 29 swings. Mounted on the arm 29 is a second arm 32, this arm being pivotally connected to the arm 29 at a point 33 which is adjacent or near the pivoted end of the arm 29. The free end of the arm 29 is forked, it being provided with two parallel projections 34 and 35. A link member 36 extends vertically between the projections 34 and 35 and has its upper end pivotally connected to the arm 32, and its lower end pivotally connected to a central lug 37 on the cover 19. A lever 38 is pivoted near one end at point 39 between the ends of the projections 34 and 35. The two portions 38^a and 38^b of the lever 38 are at an angle with respect to each other which is somewhat less than 90 degrees, and when the cover is in

place the shorter portion 38^a underneath the arm 32 is substantially horizontal as indicated in Fig. 1, the longer portion 38^b then extending substantially vertically upward. 5 A roller 39 is provided on the extremity of the shorter portion 38^a.

In the operation of this mechanism, when it is desired to remove the cover, lever 38 is pulled down to a substantially horizontal 10 position, as indicated in Fig. 2. This raises the shorter portion 38^a whereby the arm 32 is raised, the roller 39 bearing against the lower edge of the arm 32. When the cover is in raised position, as shown in Fig. 2, it 15 will be observed that the longer portion 38^b of the lever 38 is substantially horizontal, and extends across the furnace in position to be conveniently grasped by the operator to swing the arm 29 to one side and thereby 20 move the cover to one side of the furnace opening 16. The shorter portion 38^a is then inclined slightly with the vertical toward the left, as viewed in Fig. 2, whereby the weight of the door tends to turn the lever 38 in a 25 counterclockwise direction. Further turning of the lever 38 in a counterclockwise direction is prevented, however, by means of projections or flanges 40 extending from each side of the arm near its pivot which abut 30 against flattened portions 41 on the ends of the projections 34 and 35 of the lever. When the cover is in lowered position, as indicated in Fig. 1, the arm 38 rests against the end of the arm 32.

35 A small switch 42 is mounted on the arm 29 just above the arm 32. This switch is operated by means of a button 43 which is in position to be engaged by the arm 32 and moved upward to open the switch when the 40 cover is lifted. The switch is biased to closed position, and when the cover is lowered it again closes. This switch is connected by means of conductors led through a flexible conduit 44 in the control circuit for 45 the heating resistors so that when the cover is lifted this control circuit is opened and the resistors deenergized.

In the modified form of my invention shown in Fig. 4 the cover 45 is secured centrally to a vertical rod 46 having its upper end threaded. This rod extends loosely through an aperture provided for it in the swinging arm 47, adjacent the end of the arm, and cooperates with a bevel gear nut 48 resting on the arm 47. It will be understood that the arm 47 is mounted to swing over the furnace in the same manner as the arm 29 of Figs. 1, 2 and 3. The bevel gear 48 may be turned to lift the cover by means 50 of a handwheel 49 which turns a horizontal shaft 50 rotatably mounted on the end of the arm 47 and carrying a bevel gear 51. As

shown, a relay switch 52 for causing the circuit of the furnace heater to be opened is mounted on the arm 47 directly above the 65 rod 46 so that when the cover is being lifted the switch is operated to open the heating circuit by the engagement of the rod 46 therewith. After being lifted, the cover can be swung to one side on the arm 47 in the 70 manner described in connection with Figs. 1, 2 and 3.

While I have described my invention as embodied in concrete form and as operating in a specific manner in accordance with the 75 provisions of the patent statutes, it should be understood that I do not limit my invention thereto, since various modifications thereof will suggest themselves to those skilled in the art without departing from 80 the spirit of my invention, the scope of which is set forth in the annexed claims.

What I claim as new and desire to secure by Letters Patent of the United States, is:

1. The combination with a furnace, of a 85 cover for said furnace, an arm supported at one side of said furnace so as to swing over said furnace, a second arm pivoted on said first arm extending lengthwise thereof, a connection between said second arm and said cover, and a lever pivoted on the end of said first arm and acting on said second arm to lift said cover.

2. The combination with a furnace, of a 95 cover for said furnace, an arm supported on one side of said furnace so as to swing over said furnace, a second arm pivoted on said first arm extending lengthwise thereof, a connection between said second arm and said cover, and a lever pivoted on the end of 100 said first arm having a shorter portion arranged approximately right angles with the remaining longer portion, said shorter portion acting on said second arm to raise said cover when said longer portion is moved 105 from a substantially vertical to a substantially horizontal position.

3. The combination with a furnace, of a 110 cover for said furnace, an arm supported on one side of said furnace so as to swing over said furnace, a second arm pivoted on said first arm, a connection between said second arm and said cover, and a lever pivoted on 115 said first arm having a shorter portion engaging said second arm to raise said cover, said shorter portion being in an inclined position when the cover is lifted whereby the weight of said cover tends to turn said lever in one direction, and means for limiting the movement of said lever in said direction.

In witness whereof, I have hereunto set my hand this 15th day of July, 1925.

ALBERT N. OTIS.

Certificate of Correction.

Patent No. 1,646,213.

Granted October 18, 1927, to

ALBERT N. OTIS.

It is hereby certified that error appears in the printed specification of the above-numbered patent requiring correction as follows: Page 1, line 41, for the word "of" read *or*; page 2, line 102, claim 2, after the syllable "ranged" insert the word *at*; and that the said Letters Patent should be read with these corrections therein that the same may conform to the record of the case in the Patent Office.

Signed and sealed this 6th day of December, A. D. 1927.

[**SEAL.**]

M. J. MOORE,
Acting Commissioner of Patents.
